UNITED STATES PATENT OFFICE

2,558,359

BURNER SYSTEM FOR WEED BURNERS

Clarence O. Henneman, Bartlesville, Okla., and
Owen L. Garretson, Roswell, N. Mex., assignors
to Phillips Petroleum Company, a corporation
of Delaware

Application April 10, 1948, Serial No. 20,326

8 Claims. (Cl. 158—53)

1

This invention relates to improvements in fuel feeding and control systems for multi-burner weed burners.

One of the objects of this invention is to provide in such a system a master burner for vaporizing the liquefied petroleum gas fuel by means of which the burners are operated so that the fuel is supplied to all of the burners including the master burner as a vapor.

Another object of this invention is to provide a novel form of fuel supply system to a plurality of burners including such master burners whereby the operation of the apparatus is simplified and rendered more dependable.

Another object of this invention is to provide a multi-burner liquefied fuel system having a minimum of fuel feed lines in the system.

A still further object of the invention is to provide a system of this type the major portion of which may be installed on a tractor trailer.

Other and more detailed objects of the invention will be apparent from the following description of the embodiment thereof illustrated in the attached drawings.

This invention resides substantially in the combination, construction, arrangement and relative location of parts all as will be described herein-after.

In the accompanying drawings—

Figure 1 is a diagrammatic and schematic illustration of a system embodying the features of this invention; and

Figure 2 is a longitudinal central cross sectional view through the master burner.

An understanding of the operation of the complete system is facilitated by an understanding of the construction of the master burner so that the construction in Figure 2 will be described in detail.

The master burner comprises a two part housing consisting of the body portion 1 and the nozzle portion 2 held together at their flanged ends by means of nuts and bolts 3. The body portion 1 includes an extension 4 having a passage 6 therethrough terminating in a chamber in the spherical end 5. The torch portion 2 of the housing has an annular chamber 9 communicating with the passage 6. The spherical end 5 has a threaded port 7 to which the pipe 34 is connected and an axial threaded port to which the pipe 33 is connected. This port also is provided with an internally projecting tube 8 which extends through the passage 6 and into the annular chamber 9 and terminates at an open end 10. The inner wall of the annular chamber 9

2

defines the torch passage 11 into which the fuel is discharged through the nozzle orifice 15 of a demountable nozzle 14. This nozzle is mounted on a tubular reentrant element or bushing 13 of the housing part 1. This bushing together with the nozzle 14 forms a chamber into which the threaded port 16 opens and to which a pipe 37 is connected. The burner nozzle orifice is at 12 and at 12' is indicated the position of the ignitor, commonly a spark plug.

A complete four-burner system employing the master burner of Figure 2 is illustrated in Figure 1. The master burner is indicated by the reference character M. The burners are mounted on skids of the type commonly used for this purpose and illustrated in the form of standards having the plates 25 shaped to slide along the ground. Adjustably mounted on the standard 24 are a series of brackets 26 provided with clamps 20 to engage the ball shaped extensions of the burners which are similar for all the burners and are similar in this respect to that shown in Figure 2. It will be recognized that there results a ball and socket support which permits proper angular adjustment of the various burners and the clamping in adjusted position. The details of construction of the supporting mechanism form no part of this invention and therefore have not been shown in detail.

Likewise, the burners 21, 22 and 23 may be of any suitable construction and have not therefore been further illustrated although it will be recognized that the construction could be like that of Figure 2 with the elimination of the vaporizing adjunct which characterizes the master burner M of Figure 2. It will also be recognized that the apparatus can be constructed to include more than four burners when more than two rows of planting are to be freed of weeds simultaneously.

The fuel tank for the liquefied petroleum gas or equivalent fuel is illustrated at 27. This tank is provided with a gas take-off line 28 at the top and a liquid take-off line 41 in the form of a dip tube as commonly used in this art. The lines 28 and 41 are provided with the manual valves 29 and 42, respectively, and are interconnected as shown. At the interconnection is a 45 branch to the pressure regulator 30. The outlet port of the pressure regulator is connected by pipe 31 to a two-way valve 32. One of the branch lines 33 controlled by this valve is connected to the master burner as illustrated in Figure 2. Line 34 is connected to the other branch line 33'

controlled by the valve 32 and to one side of a manual valve 35. The other side of this valve is connected to the fuel manifold 36. This manifold is provided with the branch 37 which connects to the master burner as illustrated in Figure 2, and branches 38, 39, and 40 which connect to the remaining burners 23, 22 and 21, respectively. A bypass line 43 having a check valve 44 therein interconnects line 31 with the point of connection between lines 28 and 41 for a purpose to be described later. Pipes 34 and 37 are interconnected by a bypass 34' having a needle valve 45 for a function to be described later. A valve 37' is included in the line 37 which may be a manual valve or a back-flow check valve like the valve 44.

In the operation of this system, it is started up by opening valve 29, valve 42 being closed. Fuel gas flows from the vapor space in the tank 27 through line 28, valve 29, pressure regulator 30 where its pressure is reduced to the proper value, line 31 and to valve 32. Valve 32 is positioned to interconnect line 31 with line 34. Upon opening valve 35 this gas is delivered to the manifold 36 by means of the branches 37, 38, 39 and 40, to the master burner M and the standard burners 23, 22, and 21, respectively. If valve 37' is a manual valve it will be open at this time or if it is a check valve it is placed in line 37 to permit gas to flow to the burner M. Thus, all of the burners can be put in operation at the time of starting up. As an added feature, when it is desired to cut off all burners except the master burner, it can be provided with a passage P in the body portion 1 interconnecting the passage 6 directly with the nozzle 14 in which case, with the valve 32 in the position shown and valves 35, 45 and 37' (if a manual valve) closed, vapor can be supplied directly to the master burner only from the vapor space of the tank 27 through the same circuit. Valve 37' prevents vapor from reaching the manifold 36 through line 37.

In either event, as soon as the master burner has warmed up, valve 29 is closed, valve 42 is opened and valve 32 is positioned to interconnect pipe 31 with pipe 33 (as shown) whereupon liquid will be withdrawn to the inlet of the pressure regulator through the dip tube 41 and valve 42. Liquid fuel is then delivered from the regulator to the master burner through the line 31, valve 32 and line 33 to tube 8 within the master burner from which it is discharged into the space 9 at the open end 10 of this tube. The liquid in the chamber 9 is then vaporized and returned through passage 6 to line 34, valve 35 and manifold 36 from which it flows to all of the burners including the master burner (valve 37' being open if a manual valve). Thus, for conditions of operation where the ambient temperature is not sufficiently high to cause the conversion of enough of the liquid in tank 27 to a vapor to operate the burners through the connection 28, it is possible to supply the required amount of vapor by using the master burner as a vaporizer.

The hand operated valve 35 is a standard quick opening valve which does not throttle but is either fully open or fully closed. Therefore, when the burners are shut down, but it is desired not to kill the flame, valve 35 may either have a leak passage therein to supply sufficient gas to keep the burners lit or a bypass connection may be provided between the lines 34 and 36 or 37 through valve 45 to supply enough gas to the manifold 36 to keep the burners lit. This valve

45 may be an adjustable needle valve for adjusting to attain such operation.

With this arrangement a quick snap on and off action is provided without extinguishing the burners unless the needle valve 45 is closed. The two-way valve 32 permits the operator to shunt vapor directly from the vapor space of the tank 27 to the manifold 36 at those times when he wishes to operate on vapor alone which particularly may be the condition when the ambient temperature is high enough.

Should the bypass 45 not be employed and should the valve 35 be closed after the system has been in operation, the liquid in line 33 would continue to vaporize in the master burner and build up excessive pressures in the line 31. To relieve this condition, the bypass line 43 with its back flow check valve 44 is provided to shunt the gas and liquid back into the tank 27 around the pressure regulator 30 through the bypass line 43 and thereby relieve the pressure in this part of the system.

It will be recognized that the use of the bypass P (Figure 2) prevents the snap on and off action 25 of the master burner. It is therefore advantageous to pipe all vaporized fuel from the master burner back to the manifold 36 through line 34 so that snap on and off action for all burners including the master burner is possible when 30 required. If a reduced flame is not considered necessary for the master burner bypass P eliminates the line 37.

There are many advantages of this system. The use of a master burner permits a construction 35 of a weed burner unit that requires only tow bar attachment to the tractor as heat is not required from the tractor exhaust to perform the vaporizing operation. Furthermore, by returning the vapor from the master burner to the manifold the use of liquid feed lines is limited, reducing the hazard from failure of equipment. The use of the valve 35 to cut off the flow of vapor results in fractional control of the burner flame whereas with liquid feed the burners 40 would continue to operate for some time after shut-off. This flexibility of the vapor system is highly advantageous as it will permit cut-off of burners when burning the weeds about small plants such as might be met in some part of a row of plants where the plants have not grown to as large a size as in other parts of the row. This system also permits the reduction of gas consumption by cutting off the gas supply at the time the tractor is turning around at the end of the field.

In other words, by operating on vapor, a snap action results which permits instantly cutting the burners down to the point where they just stay lit during periods when they are not being used.

It will be understood that where a larger number of burners are used and sufficient vapor is not supplied by one master burner more than one master burner may be employed.

From the above description it will be apparent to those skilled in the art that the subject matter of this invention is capable of some variation and we do not therefore desire to be limited to the single embodiment herein illustrated but rather to the claims granted us.

What is claimed is:

1. In a system of the type described, the combination comprising a fuel vapor manifold, a plurality of fuel vapor burners connected to said manifold, at least one of said burners having a

liquid fuel vaporizer in heat exchange relation therewith, a source of liquid and vaporized liquid fuel, means for selectively delivering liquid or vapor fuel from said source to said burner, means for delivering vapor fuel from said vaporizing means to said manifold, said last means including an on and off valve for controlling the supply of vapor fuel to the manifold and means for supplying a limited quantity of fuel to said manifold when said on and off valve is closed.

2. In the combination of claim 1, said first mentioned means comprising a valve and pipe connections whereby vapor may be delivered from said fuel source to said burners for one position of that valve.

3. In the combination of claim 1, said first mentioned means comprising a valve and pipe connections whereby vapor may be delivered from said fuel source to said burners for one position of that valve and liquid can be delivered to said vaporizing means for another position of that valve.

4. A system of the type described comprising a fuel source of liquefied gas, a fuel supply line, means for delivering liquid or gas to said line from said source, a gas manifold line, a plurality of burners individually connected to said manifold line, one of said burners having a vaporizing unit in heat exchange relation therewith, means including a valve for delivering gas to said manifold or liquid to said vaporizer from said source, and a pipe connection from said vaporizer to said manifold line.

5. In the combination of claim 4, means for controlling the supply of gas to the manifold from either said source or said vaporizing means.

6. In the combination of claim 4, means for controlling the supply of gas to the manifold from

either said source or said vaporizing means, and a bypass connection around said last means for supplying a limited quantity of gas to said manifold line from said source.

- 5 7. In the combination of claim 4, a pressure regulating valve in said fuel supply line.
8. In the combination of claim 4, a pressure regulating valve in said fuel supply line, and means for returning fuel around said pressure regulator from said fuel supply line to said fuel source when pressure in said fuel supply line exceeds a predetermined value.
